UNITED STATES PATENT OFFICE

FRED PREMO, OF KENOSHA, WISCONSIN, ASSIGNOR OF ONE-HALF TO BARTLET FRANK VAURUSKA, OF KENOSHA, WISCONSIN

MAP HOLDER AND DISPLAY RACK

Application filed January 14, 1929, Serial No. 332,264. Renewed September 24, 1931.

This invention relates to mechanism susceptible to many varied uses but principally designed for use in connection with the display of roller maps, window shades or the like. This invention further relates to racks for supporting a plurality of the articles to be displayed, preferably one at a time, the arrangement being such that the articles supported by the rack can readily be moved from stored position adjacent a wall or the like to position for use wherein the articles are disposed, by preference, in a substantially horizontal plane common to all.

The principal objects of the invention are to provide a folding display rack of the class above described which is easily foldable from folded position to unfolded position or vice versa; to provide a rack of comparatively few and simple parts which may be quickly and easily manufactured and assembled to form the rack at a relatively small cost; to provide a rack which may conveniently be enclosed in a cabinet when in folded position; and in general, to provide an improved rack of the class described.

Other objects and advantages of the invention will become apparent when reference is had to the following specification and accompanying drawings in which I have illustrated a map rack embodying a preferred form of my invention and also a number of modified forms or uses for the mechanism constituting the principal part of my improved display rack.

55 In the drawings:

Fig. 1 is a perspective showing the general appearance of a typical cabinet enclosing a map rack made according to my invention;

Fig. 2 is a front elevation of the cabinet shown in Fig. 1, the doors being open so as to show the map rack inside of the cabinet;

Figs. 3 and 4 are sections on the line 3—3 and 4—4 respectively of Fig. 2;

Fig. 5 is a front elevation of part of the mechanism shown in Fig. 4 and corresponds to a part of Fig. 2 but on a larger scale than Fig. 2;

Fig. 6 is a section on the line 6—6 of Fig. 3;

Fig. 7 is a front elevation similar to Fig. 5 but showing a modified form of mechanism;

Fig. 8 is a section illustrating a detail of construction of a part of the mechanism shown in Fig. 7;

Fig. 9 is a side elevation similar to Fig. 4 but showing the mechanism adapted to another use;

Fig. 10 is a front elevation of part of the mechanism shown in Fig. 9;

Figs. 11 and 12 illustrate part of my mechanism adapted to a third use; and

Fig. 13 is an illustration of a detail of construction for adapting mechanism to a fourth purpose.

Referring to the drawings, particular reference being had to Figs. 1 to 6 inclusive, my improved display rack includes a cabinet having a back wall 15, side walls 16—16, and a pair of front doors 17—17, which are hinged to opposite side walls so as to be capable of being swung to open position for affording access to the interior of the cabinet. A pair of horizontally spaced, vertically disposed guide rods 18—18 are mounted on the back wall 15 of the cabinet through the agency of top and bottom brackets 19 and 20, respectively, the said brackets being secured to the back wall 15 in any suitable manner, for instance, by means of screws as indicated at 21 in Figs. 4 and 5. The guide rods 18 are secured in the brackets 19 and 20 preferably by having their end portions reduced, as indicated at 22 and headed over as shown at 23 in Fig. 4.

An arm 24 is associated with each of the said guide rods 18 and is connected at its lower end to the guide rod so that it is capable of pivotal or folding movement relative to the guide rod and also sliding movement axially of the guide rod. One means for so connecting the lower end of the arms 24 and the respective guide rods 18 consists of a member 25 (Fig. 6) which is bent around the guide rod to form an enlarged circular portion 26 which is slidable along the guide rod and ears or lugs 27—27 which embrace the lower end of the respective arms 24 and through which ears and arm portion a pivot pin 28 passes. Hence, it will be seen that each of the arms 24 may be swung outwardly, with

100

respect to the guide rods, from folded position, as shown in Figs. 3 and 4.

For controlling the folding or unfolding movement of the arms 24, I provide links such as 29—29 which are pivotally connected at their upper ends as shown at 30, to lugs 31 which are provided as an integral part of the upper brackets 19. The lower ends of the links 29 are pivotally connected as shown at 32 to a portion of the respective arms 24 intermediate their ends. By an inspection of Fig. 3, it will be seen that the arms 24 may be swung from folded position, as shown in full lines, to unfolded or extended position, as shown in dotted lines. When the arms are to be moved from folded position as shown, the upper ends of the arms are folded outwardly so that the arms swing about the lower end link pivots as fulcrums, whereby the lower end parts of the arms slide upwardly along the respective guide rods while also turning about the lower end pivots 28.

The lower end link pivot is preferably located on the arms 24 in such a way that the upper or outer end portion of the arms will over-balance the inner end portions. By this arrangement, the over-balancing weight renders the rack easily unfolded. Folding of the rack is also quite easily accomplished since the excess of weight on the outside of the lower end link pivot is only sufficient to over-balance the inner part of the arms and hence need not be so great as to cause any difficulty to the operator in raising the outer end or lowering the inner end of the rack for moving the same to folded position. For limiting the unfolding movement of the arms 24, I provide brackets 33—33 which embrace intermediate parts of the guide rods 18—18 and are secured to the back wall 15 of the cabinet. The brackets 33 are preferably so positioned along the guide rods 18 that the members 25 will engage the lower ends of the respective brackets to stop further pivotal movement of the respective arms when a substantially horizontal position is reached, as indicated in broken lines in Fig. 3. The brackets 33 also serve to prevent bending or buckling of the guide rods 18 so that comparatively light weight rods may be used.

The arms 24—24 are connected together by means of one or more tie rods as shown at 34, so that the arms constitute in effect a unitary frame which is pivotally movable about the lower end link pivots and slidably as well as pivotally movable at its lower end relative to the guide rods. The arms are provided with suitable apertures and slots for facilitating mounting thereon of a plurality of roller maps such as indicated at 35—35. These roller maps may be of any well known type but are preferably of the type in which the map is carried by a spring roller which automatically winds the map upon itself when a suitable ratchet locking mechanism

is disengaged. The maps may be provided with end sticks 36 which are of such length that end portions project over the arms 24—24 to stop the winding of the maps on the rollers.

It will be understood from an inspection of Figs. 3 and 4 that when the doors 17—17 of the cabinet are opened, the maps may be pulled out and displayed while the rack remains in vertical or folded position if desired. This may be convenient in cases where one of the lowermost maps is to be displayed and in other cases, the rack may be swung to extended or unfolded position where all of the maps are conveniently accessible. The weight of the maps and arms is supported by the links 29—29 assisted by spring cushions 37—37 which are disposed around the lower ends of the guide rods 18—18 and adapted to receive the members 25—25 when the rack is moved to folded position. The spring cushions 37 are preferably of such length that they will serve as shock absorbers to prevent slamming of the rack into folded position. For yieldingly or releasably holding the rack in folded position, I provide a spring clip 38 which is secured to the back wall of the cabinet and yieldingly hooks over the upper tie rod 34. The doors 17—17 of the cabinet may conveniently be maintained in closed position by means of spring catches such as shown at 39 and 40, at the upper and lower ends of the doors.

The map rack structure above described is quite simple in character and obviously can be manufactured at a minimum of expense. It also presents a neat and pleasing appearance when unfolded for use because of its simplicity and when folded, because all of the mechanism is contained inside of the cabinet which may be suitably ornamented.

Instead of pivotally connecting the upper ends of the links 29 to ears made integral with the upper brackets 19 as above described, I may pivot the said upper ends directly to the guide rods 18 as shown in Figs. 7 and 8. In this construction, a spacing sleeve 41 is provided between the respective guide rods and links to maintain the same in proper spaced relation, and pivot pins 42, extending through the sleeves 41 and suitable apertures in the guide rods and links may be provided and headed over as shown in Fig. 8, to permanently retain the same in place. This construction avoids the necessity of providing a special bracket for mounting the upper ends of the guide rods and permits the use of a simple angle iron bracket such as used for mounting the lower end.

Referring now to Figs. 9 and 10, I have shown a guide rod 18a, an arm 24a and a link 29a respectively connected in substantially the same manner as are the parts 18, 24 and 29 of the map rack structure above described.

In this instance, the arm 24a is provided with a plurality of cross arms 43-43 over which other articles to be displayed may be hung or which may be provided with a plurality of clips such as shown at 44 for suspending various articles from the cross arms. In this instance, the lower end of the link 29a is offset as indicated at 45 so that the link will not engage one of the cross arms 43 which engagement would prevent folding of the arm to completely folded position.

In Figs. 11 and 12, I have shown folding rack mechanism substantially the same as that described above in connection with a map rack but modified to support and control an awning which consists of a ratchetless spring roller 46 on which the desired fabric or other material 47 is wound. In this instance, the upper mounting brackets are mounted adjacent the upper end of the window with which the awning is associated and each of the brackets is provided with an upwardly extending ear or flange 48. These ears or flanges are apertured or slotted to receive the ends of the spring roller 46. In this case only one tie rod 49 is provided between the arms 24-24, this one tie rod being located at the upper or outer ends of the arms and to which tie rod the outer end of the awning is secured in any suitable manner as indicated in Fig. 11. It will be seen that when the arms are swung to unfolded position, the awning will be stretched outwardly a considerable distance from the face of the wall indicated at 50. Also that the awning is maintained at a high elevation relative to the window so that it does not cut off the light from the window over which the awning is positioned.

In Fig. 13, I have shown a portion of an arm 24b which corresponds to one of the arms 24 of the map rack or the arm 24a of Figs. 9 and 10 and in this instance, the arm is provided with a plurality of slots such as shown at 51. These slots extend inwardly from one edge of the arm and then outwardly again so as to form a hump portion 52. It will be seen that the hook of a coat hanger or the like may readily be positioned or guided into the slot 51 by simply engaging the hook against the edge of the arm and then moving the hook along the said edge until the hook enters one of the slots. When the arm 24b is moved from vertical, folded position to unfolded or horizontal position, the hump part 52 will serve to retain the hook of the coat hanger in the slot while at same time permitting the hook to be readily removed when desired. The slots will be located in spaced relation lengthwise of the arm so that a plurality of garments may be supported thereby. When the arm is in folded position, the garments will hang flat, one over the other, against the wall, door or other surface to which the device is secured. In such position,

the garments will take up only a minimum of space, for which reason the device is highly desirable in a coat closet or the like where space ordinarily is not plentiful. When the arm is swung to horizontal position, the garments hang free of each other and are readily removable from the rack.

I am aware that changes may be made in the form, construction and arrangement of parts of my improved display rack mechanism without departing from the spirit of the invention, the scope of which should be determined by reference to the following claims, the same being construed as broadly as possible consistent with the art.

I claim as my invention:

1. In a folding display rack, the combination of a supporting frame including a guide rod, an arm connected adjacent its lower end to said guide rod so as to be slidably and pivotally movable relative thereto, and a link, pivotally connected at one end to said arm intermediate the ends of the latter and at its other end to a stationary part of said supporting frame.

2. In a folding rack of the class described, the combination of a supporting frame including a vertically disposed guide rod, an arm connected adjacent its lower end to said guide rod so as to permit outward swinging movement of the upper end of said arm and simultaneously therewith, upward movement of the lower end of the arm relative to said guide rod, a link pivotally connected at its upper end to a stationary part of said supporting frame and at its lower end to said arm intermediate the ends of the latter, said lower pivotal connection serving as a fulcrum for said arm when the upper end thereof is swung upwardly, said lower end of said link being offset so as to permit complete folding of said rack to a vertical position.

3. In a folding rack of the class described, the combination of a supporting frame including a vertically disposed guide rod, an arm connected adjacent its lower end to said guide rod so as to permit outward swinging movement of the upper end of said arm and simultaneously therewith, upward movement of the lower end of the arm relative to said guide rod, a link pivotally connected at its upper end to a stationary part of said supporting frame and at its lower end to said arm at a point nearer to the lower end of the arm than to the upper end, whereby, when said arm is swung outwardly at its upper end about said lower link pivot, the upper end portion of the arm tends to overbalance the lower end portion to thereby facilitate unfolding of the rack.

4. In a folding rack of the class described, the combination of a supporting frame including a vertically disposed guide rod, an arm connected adjacent its lower end to said

- guide rod so as to permit outward swinging movement of the upper end of said arm and simultaneously therewith, upward movement of the lower end of the arm relative to said guide rod, a link pivotally connected at its upper end to a stationary part of said supporting frame and at its lower end to said arm at a point nearer to the lower end of the arm than to the upper end, whereby, when said arm is swung outwardly at its upper end about said lower link pivot, the upper end portion of the arm tends to overbalance the lower end portion to thereby facilitate unfolding of the rack, and means for limiting upward movement of the lower end portion of said arm along said guide rod whereby the weight of said upper arm portion is prevented from effecting unfolding of the rack beyond a predetermined limit.
5. In a folding rack of the class described, the combination of a supporting frame including a vertically disposed guide rod, an arm connected adjacent its lower end to said guide rod so as to permit outward swinging movement of the upper end of said arm and simultaneously therewith, upward movement of the lower end of the arm relative to said guide rod, a link pivotally connected at its upper end to a stationary part of said supporting frame and at its lower end to said arm intermediate the ends of the latter, said lower pivotal connection serving as a fulcrum for said arm when the upper end thereof is swung upwardly, and shock absorbing cushion means adjacent the lower end of said guide rod for supporting said arm when in folded position.
6. In a map rack of the class described, the combination of a pair of spaced supporting frames, each comprising a fixedly mounted, vertically disposed guide rod, an arm connected at its lower end to said guide rod so as to be vertically, slidably and pivotally movable relative thereto, and a link pivotally connected at one end to said arm intermediate the ends of the latter and at its other end to a stationary part of the frame, said links serving to support the load of said arms when in unfolded position, means for relieving said links of part of said load when said arms are in folded position, and a tie rod connecting said arms together so as to form therewith a unitary folding frame, and a plurality of roller maps carried by said arms.
7. In a map rack of the class described, the combination of a pair of spaced supporting frames, each comprising a fixedly mounted, vertically disposed guide rod, an arm connected at its lower end to said guide rod so as to be vertically slidably and pivotally movable relative thereto, a link pivotally connected at its upper end to a stationary part of said frame and at its lower end to a point on said arm intermediate

the ends of the latter but nearer to the lower end than to the upper end, tie rods connecting together the arms of said spaced frames, and a plurality of roller maps carried by said arms, the arrangement being such that the weight of the maps on the arm portion above said lower link pivot is greater than the weight of the maps and arm parts below said pivot, said greater weight serving to over-balance the lesser when said supporting frame is swung about said lower end linked pivot from folded position to unfolded position, thereby facilitating unfolding of the rack.

8. In a map rack of the class described, the combination of a cabinet including a back wall, side walls, and a hinged front door affording access to the interior of the cabinet, a supporting frame in said cabinet, comprising a pair of horizontally spaced, vertically disposed guide rods, fixedly mounted on said back wall but spaced outwardly therefrom, spacer members secured to said rear wall and said guide rods intermediate the ends of the latter for maintaining the intermediate portions of said guide rods in fixed spaced relation to said back wall, a pair of arms respectively associated with said guide rods and connected at the lower ends to said guide rods so as to be pivotally and slidably movable relative thereto, a pair of links respectively associated with said arms, pivotally connected at their upper ends to fixed parts of the frame and at their lower ends to said arms intermediate the ends of the latter said lower end link pivots serving as a fulcrum on which said arms are movable from vertical, folded position to horizontal, unfolded position, the upper end portions of said arms swinging outwardly and downwardly and their lower end portions sliding upwardly along said guide rod, tie rods connecting said arms for maintaining the same in fixed spaced relation, and a plurality of roller maps carried by said arms.

9. In a map rack of the class described, the combination of a cabinet including a back wall, side walls, and a hinged front door affording access to the interior of the cabinet, a supporting frame in said cabinet, comprising a pair of horizontally spaced, vertically disposed guide rods, fixedly mounted on said back wall but spaced outwardly therefrom, spacer members secured to said rear wall and said guide rods intermediate the ends of the latter for maintaining the intermediate portions of said guide rods in fixed spaced relation to said back wall, a pair of arms respectively associated with said guide rods and connected at the lower ends to said guide rods so as to be pivotally and slidably movable relative thereto, a pair of links respectively associated with said arms, pivotally connected at their upper ends to fixed parts

- of the frame and at their lower ends to said arms intermediate the ends of the latter, said lower end link pivots serving as a fulcrum on which said arms are movable from vertical, folded position to horizontal, unfolded position, the upper end portions of said arms swinging outwardly and downwardly and their lower end portions sliding upwardly along said guide rod, whereby said link serves to support said folding arms when in unfolded position, and spring cushion means adjacent the lower ends of said guide rods for relieving said link of a part of the load of said arms.
- 10 10. In a device of the class described and in combination, a vertical rod, an arm mounted at its lower end on said rod for pivotal movement and also for sliding movement along said rod, a link pivoted to said arm and pivotally secured to said rod adjacent the upper extremity thereof.
- 15 11. In a device of the class described and in combination, a vertical rod, an arm mounted at its lower end on said rod for pivotal movement and also for sliding movement along said rod, a link pivoted to said arm intermediate of the ends of said arm and pivotally secured to said rod adjacent the upper extremity thereof.
- 20 12. In a device of the class described and in combination, a vertical rod, an arm mounted at its lower end on said rod for pivotal movement and also for sliding movement along said rod, a link pivoted to said arm intermediate of the ends of said arm and between the mid-point thereof and the end of said arm which is secured to said rod, said link being pivotally secured to said rod adjacent the upper extremity thereof.
